No. 732,924.

Patented July 7, 1903.

UNITED STATES PATENT OFFICE.

JOHN B. CUZNER, OF GLASTONBURY, CONNECTICUT.

TOBACCO-HANGER.

SPECIFICATION forming part of Letters Patent No. 732,924, dated July 7, 1903.

Application filed February 7, 1903. Serial No. 142,331. (No model.)

To all whom it may concern:

Be it known that I, JOHN B. CUZNER, a citizen of the United States of America, residing at Glastonbury, in the county of Hartford and

5 State of Connecticut, have invented certain new and useful Improvements in Tobacco-Hangers, of which the following is a specification.

Figure 1 is a general side view of the preferred form of my invention. Fig. 2 is a similar view to Fig. 1, but with the link, hooks, and rod folded against the lath. Fig. 3 is a view of a modification.

In the drawings, *a* denotes a lath similar to 15 those used for hanging tobacco. *b* is a link suspended therefrom and having attached to it the rod or wire *c* or its equivalent, upon which the tobacco is strung. In the claim this part *c* will be referred to as the string, 20 although it is preferably made from stiff material, such as wire rod.

d e are hooks depending from the lath and provided as a support for the rod or wire, as clearly indicated in the drawings.

25 The manner of use of the device is readily seen.

In Fig. 2 the link *b* and the hooks *d e* are

shown swung up against the lath. This provision is made in order that the laths when not in use may be stacked up and occupy a 30 minimum amount of room.

The modification illustrated in Fig. 3 is similar to the preferred form shown in Figs. 1 and 2, with the exception that the links and hooks are double instead of single. This 35 double link is shown at *b'* and pivoted to the top of the lath, as at *b''*. When the lath is not in use, these double links and hooks are turned to the position indicated in dotted lines, permitting the laths to be conveniently 40 and compactly stored away.

I claim as my invention—

The combination with the lath, of the depending link, the string secured at one end thereof, and one or more depending hooks for 45 supporting the opposite end of said string, said link and hooks being pivotally supported on the lath.

In testimony whereof I affix my signature in presence of two witnesses.

JOHN B. CUZNER.
